Jack M. Pun

BY

George S. Webster

ATTORNEY

UNITED STATES PATENT OFFICE.

JACK M. PUN, OF STOCKTON, CALIFORNIA.

SHIPPING-REFRIGERATOR.

1,370,044.

Specification of Letters Patent. Patented Mar. 1, 1921.

Application filed March 25, 1919. Serial No. 285,045.

To all whom it may concern:

Be it known that I, JACK M. PUN, a citizen of the United States, residing at Stockton, in the county of San Joaquin, 5 State of California, have invented certain new and useful Improvements in Shipping-Refrigerators; and I do declare the following to be a full, clear, and exact description of the same, reference being had to the accompanying drawings, and to the characters of reference marked thereon, which form a part of this application.

This invention relates to improvements in portable refrigerators, and particularly to a 15 type adapted for shipment on trains or trucks to carry "dry-chilled" products such as poultry, game, etc., which it is not desired shall come into actual contact with ice.

The principal object of the invention is 20 to provide a refrigerator having a container or compartment for the goods being shipped which will have the chilling effect of the ice all around it and which is so constructed that no ice or ice-water can get in and mix 25 with the contents thereof, and in which a circulation of cold air is maintained, thus preventing the stale, metallic taste and odor common in refrigerated articles.

I have also produced a refrigerator 30 adapted to be returned to the point of shipment and used again indefinitely.

Another object is to provide a light, simple and inexpensive device and yet one 35 which will be exceedingly effective for the purposes for which it is designed.

These objects I accomplish by means of such structure and relative arrangement of parts as will fully appear by a perusal of the following specification and claims.

On the drawings similar characters of 40 reference indicate corresponding parts in the several views.

Figure 1 is a perspective elevation of my improved refrigerator, with the cover of the 45 container removed.

Fig. 2 is a transverse cross section thereof showing the covers in place.

Fig. 3 is an enlarged fragmentary section 50 showing the sides overlapping and the air vents formed thereby.

Referring now more particularly to the characters of reference on the drawings, 55 numeral 1 denotes the outside box of the refrigerator of any desired shape and size and preferably lined with zinc 2 spaced from the material of the box as is common

custom. A hinged lid 3 is provided on the box adapted to be fastened down in any suitable manner as by a hasp-lock 4. A handle 5 is provided on each end of the box, 60 and drainage holes 6 in the bottom thereof, which is spaced from the floor by cleats 7.

Positioned in the box 1 and secured to the bottom thereof is a container 8, the same being spaced equally from the sides and 65 ends of the box and with its sides and ends tapering somewhat in toward the top, pyramidwise. The container is preferably constructed in a substantial manner of some non-corrosive sheet metal such as zinc. 70

The sides of the container are formed in two sections 9 and 10 longitudinally, the upper section 9 overlapping the lower section somewhat as at 11 and being spaced therefrom by spacer bars or blocks 11^a to 75 form air vents 11^a therebetween, at the same time preventing any ice from falling into the container when ice is being packed therearound. The ends 12 of the container are slightly higher than the sides thereof but 80 considerably lower than those of the box 1, and a cover or lid 13 is adapted to rest thereon, this lid extending beyond the plane of the sides so that no ice can fall into the container through the air vents 14 formed by 85 the sides being lower than the ends.

The bottom 15 of the container is spaced somewhat from the bottom of the outer box, the same resting on cleats 16 through which the container is secured to the box 1. 90

In operation, after the goods are placed in the container and the lid 13 placed thereon, ice is packed all around and over the same, and the lid 3 fastened down. As the ice melts and water forms, the same drips out 95 through the drains 6, the space in the box 1 under the container always remaining cold whether ice or water is actually present thereunder or not, for the reason that the cold air present will always drop to the 100 lowest point.

Any air in the container warmer than the surrounding atmosphere will pass out through the upper vents 14, its place being taken by cold air passing downward there- 105 in through the vents between the sides 9 and 10.

The overlapping sides and lid, as heretofore stated, prevent any ice from getting into the interior of the container. The 110 pyramid shape of the container is to insure a greater quantity of the cooling medium be-

ing near the top, as that portion is naturally the warmest.

From the foregoing description it will be readily seen that I have produced such a device as substantially fulfills the object of the invention as set forth herein.

While this specification sets forth in detail the present and preferred construction of the device, still in practice such deviations from such detail may be resorted to as do not form a departure from the spirit of the invention, as defined by the appended claims.

Having thus described my invention, what I claim as new and useful and desire to secure by Letters Patent is:—

1. A shipping refrigerator for dry chilled products comprising a box adapted for transportation and to contain ice, a covered container secured in the box and spaced from the inner walls and bottom thereof, and means whereby a circulation of air is maintained between the interior of the container and the box through the sides thereof, but ice is prevented from entering therein.

2. A shipping refrigerator for dry-chilled products comprising a box adapted for transportation and to contain ice, a container secured in the box and spaced from the inner

walls thereof, and means whereby a circulation of air is maintained between the interior of the container and the box, but ice is prevented from entering the container, such means including longitudinally and downwardly lapped sides on the container, such lapped portions being spaced from each other, whereby air vents are formed, and a cover on the container projecting beyond the plane of the sides and being spaced therefrom to form a longitudinal slit on each side therebetween.

3. A shipping refrigerator for dry-chilled products comprising a box adapted for transportation and to contain ice, a covered container secured in the box and spaced from the inner walls thereof, such container having longitudinal and downwardly lapped sides, such lapped portions being spaced from each other, whereby air vents are formed but ice is prevented from entering the container.

In testimony whereof I affix my signature in presence of two witnesses.

JACK M. PUN.
